REFRIGERATING APPARATUS

Ralph W. Doeg, Detroit, Mich., assignor to American Motors Corporation, a corporation of Maryland

Application September 15, 1952, Serial No. 309,610

4 Claims. (Cl. 137—512.15)

This invention relates to refrigerating apparatus and more particularly to refrigerant compressors and the discharge valve mechanism therefor.

One of the objects of the invention is to provide an improved compressor discharge valve mechanism of a character to decrease valve operating noise and prolong usefulness of the valve.

Another object of the invention is to provide improved compressor discharge valve mechanism in which valve slap noise of a thin resilient pressure responsive reed valve or closure strip is substantially eliminated by convex stop surfaces and by restricting flexing of the valve to portions thereof in the immediate vicinity of the discharge ports.

Another object of the invention is to provide, for controlling a pair of discharge or outlet ports, a single pressure responsive resilient reed valve closure strip and associated mechanism arranged to dampen the noise of the closure strip operation by confining flexing thereof normally to areas of the strip directly over the ports, and in the event of undue pressure on the strip, allow for full flexing action to avoid rupture or other damage to the closure strip.

Further objects and advantages of the present invention will be apparent from the following description, reference being had to the accompanying drawings, wherein a preferred form of the present invention is clearly shown.

In the drawings:

Fig. 1 is a fragmentary view in cross section of a refrigerant compressor and discharge valve mechanism embodying features of my invention;

Fig. 2 is a view similar to Fig. 1 showing certain parts of the compressor and discharge valve mechanism in the positions they assume on discharge operation; and

Fig. 3 is a detail sectional view of my discharge valve mechanism, taken along line 3—3 of Fig. 1.

Referring to the drawings by characters of reference, there is shown a compressor cylinder block 20 having a bore 22 in which a piston 24 is adapted to reciprocate to compress gaseous refrigerant. A valve body or plate 26 covers the outer end of cylinder bore 22 to form a compression chamber therewith, and mounted on said plate is a head 28. Screws (not shown) or other suitable securing means may be provided to hold the block 20, valve plate 26, and head 28 together, and to displace suitable gaskets 34 to insure fluid tight joints between the parts.

In the valve plate 26 is an inlet port 36 and a pair of laterally positioned outlet or discharge ports 38 that overlie the outer end of the cylinder for communication therewith. Within the cylinder head 28, a partition 40 separates inlet port 36 from outlet ports 38.

Held between gasket 34 and the under surface of valve plate 26 is a thin resilient reed suction valve or resilient plate 42 which closes inlet port 36 on the compression stroke of the piston and opens the port on the suction stroke of the piston. Any suitable type of suction valve

2

may be used for controlling the inlet port, such for example as the valve shown in my Patent #2,372,938 issued April 3, 1945.

Controlling the refrigerant discharge ports 38 is my improved valve mechanism which includes a resilient valve member or closure strip 44 and a valve stop or backing plate 46. The resilient closure strip 44 overlies both of the ports 38, and the backing plate is arranged to overlie the closure strip 44 such that the closure strip is disposed between the opposed surfaces of the plates 26, 46. Backing plate 46 is located by a pair of parallel pins 48 which have free fit with the plate to allow slight movement thereof toward and away from valve plate 46. The pair of pins 48 are respectively located outwardly of ports 38 and are fixed to valve plate 26. The pins 48 extend through the backing plate 46, and the outer ends of the pins support a stop member or rigid metal strip 50 which holds a leaf spring 52 under tension against backing plate 46 for yieldingly urging the plate 46 against valve plate 26.

Outer end portions of the resilient closure strip 44 are free to slide inwardly and outwardly to effect flexing, and in so doing aid in decreasing valve slap against the backing plate. The ends of the closure strip 44 are preferably slotted, as at 54, to receive and to be guided by the pins 48. Also the inner face of the backing plate 46 is recessed as at 56 for respectively receiving the end portions of the closure strip, the recesses being sufficiently deep to allow free sliding movement of the closure strip ends. Overlying respective end portions of the closure strip 44 are valve abutting stop surfaces 58 formed on the underside of plate 46 to limit flexing action of the closure strip 44 in such manner as to decrease appreciably so-called valve slap noise occasioned in the past by the flexible strip being slapped broadside against a flat surfaced stop. To decrease such noise, I make the stop surfaces 58 convex and arrange them to overlie respectively opposite end portions of closure strip 44, and to extend from said recesses 56 inwardly and away from the closure strip to terminate at a central flat portion 62 of the backing plate 46. Thus, when closure strip 44 is flexed outwardly as occurs on the compression stroke of piston 24, the opposite ends of the closure strip slide inwardly and at the same time roll on the convex stop and in this way effect noise suppression.

In order to decrease further the operating noise of the closure strip 44, I provide a coiled spring holding means 64 for holding the closure strip 44 midway of its ends against flexing movement away from valve plate 26, thus restricting flexing action to end portions of the closure strip or to portions in the immediate vicinity of and overlying ports 38. From another aspect of the function of holding means 64 it may be said that same allows only sufficient flexing to permit unrestricted flow from ports 38 and prevents slapping and accompanying noise which would issue if the central portion of the closure member were allowed to come up against the stop plate 46. For all normal operating pressures, the spring 64 will hold the central portion of closure strip 44 against flexing. However, under certain abnormal conditions, the spring may yield and allow full flexing of the reed valve to prevent rupture thereof. The holding spring 64 is held under compression between spring 52 and the closure strip 44; the backing plate 46 being provided with a clearance hole 66 to receive the spring. Under other abnormal conditions the plate 46 may move away from valve plate 26 compressing spring 52 to allow free flow of fluid through ports 38 to prevent rupture of valve 44. Thus in some instances springs 52 and 64 may both be compressed by movement of valve 44 under abnormal conditions to permit the desired flow from ports 38.

From the foregoing description it will now be under-

stood that I have provided an improved discharge valve mechanism in which the valve or closure strip operation noise is decreased materially by my provision of convex stop surfaces which restrict the thin resilient closure strip to a sliding rolling action to avoid valve slap and accompanying noise. In addition, I have provided in said mechanism, a yieldable holding means which under normal operating conditions restricts flexing of the closure strip to small areas thereof sufficient to allow free egress from the ports controlled. In addition, the spring 64 will yield at abnormally high pressures directed against the closure strip, thus to avoid any danger of rupturing the strip or otherwise damaging the mechanism.

Although only a preferred form of the invention has been illustrated, and that form described in detail, it will be apparent to those skilled in the art that various modifications may be made therein without departing from the spirit of the invention or from the scope of the appended claims.

I claim:

1. In a compressor, a body having a pair of laterally positioned ports, a thin resilient closure strip overlying and controlling said ports and flexible away from said ports by pressure of fluid discharging therefrom, said closure strip having its opposite ends free to slide on said body to effect flexing of said resilient closure strip, means guiding sliding movement of said closure strip, convex surface stop means for said closure strip overlying only outer end portions thereof and disposed on the other side of said resilient closure strip from said body, and spring means opposing movement of said resilient closure strip at a point intermediate said ports for all fluid pressures below a predetermined pressure.

2. In a compressor, a valve body having a pair of laterally positioned ports, a thin resilient closure strip overlying and controlling said ports and flexible away from said ports by a predetermined pressure of fluid discharging therefrom, a backing plate overlying said closure strip on the other side thereof from said body, said backing plate being movable away from said body in response to a predetermined pressure higher than said first pressure acting against said closure strip, means limiting movement of said backing plate relative to said body, a leaf spring interposed between said backing plate and said means, convex stop surfaces on said backing plate facing said closure strip to limit flexing thereof, said convex surfaces curving inwardly from opposite ends of said closure strip and progressively away from said body, and a coil spring extending through said backing plate having its opposite ends respectively engaging said leaf spring and said closure strip and holding an intermediate portion of said closure strip to said body against flexing movement at pressures below said first predetermined pressure.

3. In a compressor, a valve body having a pair of laterally positioned ports, a thin resilient closure strip overlying and controlling said ports and flexible away from said ports by pressure of fluid discharging therefrom, said closure strip having its ends free to move inwardly, a backing plate overlying said closure strip on the other side thereof from said ports limiting flexing of said closure strip, pins extending through said backing plate and retained by said body, slots in opposite ends of said closure strip receiving said pins and slidably guided thereby during flexing of said closure strip, a rigid abutment member extending between and supported by said pins on the other side of said closure strip from said body, a lead spring held under tension by and between said abutment member, and said backing plate urging the latter against said body, and a spring extending through said backing plate having one end abutting said leaf spring and the other end abutting said closure strip at a point between said ports to hold a portion of said closure strip between said ports against movement during normal operating pressures.

4. In a compressor, a valve body having a pair of laterally positioned ports, a thin resilient closure strip overlying and controlling said ports and flexible away from said ports by pressure of fluid discharging therefrom, said closure strip having its ends free to move longitudinally with flexing action of the strip, a backing plate overlying said closure strip, a pair of convex surface stops on said backing plate spaced apart and respectively overlying end portions of said closure strip, said convex surfaces having curvatures extending from adjacent the end portions of said closure strip inwardly and away from the strip to present surfaces for the wrapping of the closure strip end portions thereon to decrease valve slap noise, and spring means holding an intermediate portion of said closure strip between said ports against flexing under normal pressures.
